PREPARATION OF AROMATIC HYDROCARBONS FROM HYDROCARBON MIXTURES

Ernest A. Naragon, Beacon, N. Y., assignor to The Texas Company, New York, N. Y., a corporation of Delaware

Application July 4, 1944, Serial No. 543,459

5 Claims. (Cl. 196—13)

1

This invention relates to the preparation of aromatic hydrocarbons from hydrocarbon mixtures and particularly from naphtha hydrocarbon mixtures.

The invention contemplates a process for extracting aromatic hydrocarbons from feed hydrocarbon mixtures of aromatics and non-aromatics which comprises subjecting a feed hydrocarbon mixture to contact with an aluminum halide-hydrocarbon complex of the Friedel-Crafts type. The contact is carried out under conditions so as to form a primary extract phase comprising complex aromatic hydrocarbons and some non-aromatic hydrocarbons and a primary raffinate phase consisting essentially of non-aromatic hydrocarbons such as paraffins and naphthenes. The raffinate phase is discharged and the extract phase subjected to contact with a wash solvent under conditions so as to displace non-aromatic hydrocarbons retained in the primary extract phase, leaving a secondary extract phase. This secondary extract phase, consisting essentially of complex, aromatic hydrocarbons, and a small amount of wash solvent is then subjected to contact with a further quantity of wash solvent so as to displace from the complex aromatic hydrocarbons which after separation from the wash solvent will be in a highly concentrated form.

The process is particularly applicable to the separation of aromatics from naphtha feed hydrocarbon mixtures containing aromatics amounting to from 10 to 80% by volume of the feed mixture using an aluminum chloride-hydrocarbon complex characterized by having a heat of hydrolysis of about 290 to 330 small calories per gram of complex.

The complex may be that obtained by reacting aluminum chloride with kerosene in the presence of hydrogen chloride at a temperature of about 200 to 250° F. However, the complex may comprise that which is formed in situ during the operation of the process as a result of reaction between free aluminum halide and a small proportion of the aromatic constituents of the hydrocarbons undergoing treatment.

A feature of the process has to do with the separation of aromatic hydrocarbons from non-aromatic hydrocarbons which are coextensive in boiling range. Aluminum halide-hydrocarbon complexes exert a high degree of solvent action upon aromatic hydrocarbons and this solvent action may involve some combination between the aluminum halide and aromatic hydrocarbons. However, non-aromatic hydrocarbons also tend to form combinations with aluminum halide. These

5 latter combinations are apparently of more loose character than the aromatic complex combinations.

I have found that when extracting aromatic hydrocarbons from naphtha mixtures with an aluminum chloride-hydrocarbon complex the resulting extract phase comprises complex and aromatic hydrocarbons and the resulting mixture is also more or less saturated with paraffin and naphthene hydrocarbons. It has been found that the paraffin and naphthene hydrocarbons retained in the extract phase can be displaced therefrom by washing the extract phase with a saturated hydrocarbon of different boiling range; that is, boiling outside the range of the aforesaid retained hydrocarbons.

The washing treatment can be carried out under conditions such that the retained non-aromatic hydrocarbons are displaced without substantial displacement of the aromatic constituents. Also, the washed extract phase from which the retained paraffins and naphthenes have been displaced can then be subjected to further washing, using a larger solvent dosage so as to displace aromatic hydrocarbons from the complex. The complex now stripped of aromatic hydrocarbons can then be recycled for the extraction of fresh feed hydrocarbon mixtures.

Thus, in accordance with the invention, a primary extract phase comprising complex, aromatic hydrocarbons and some non-aromatic hydrocarbons coextensive in boiling range is washed with a saturated petroleum hydrocarbon boiling in the range either substantially below or substantially above that of the extract hydrocarbons. The washing is effected in two stages. In the first washing stage, a relatively low solvent dosage is employed so as to displace the non-aromatic extract hydrocarbons, while in the second stage a relatively high solvent dosage is employed so as to displace the aromatic extract hydrocarbons from the complex. The displaced hydrocarbons removed from each washing stage are subsequently fractionated from the wash solvent liquid with which they may be associated.

Reference will now be made to the accompanying drawing showing a diagram of flow useful in carrying out the process.

Referring to the drawing, a feed hydrocarbon mixture such as naphtha or a naphtha fraction boiling in the range above about 175° F., containing about 60 volume per cent of aromatic hydrocarbons, is drawn from a source not shown and conducted through a pipe 1 to the lower 50 portion of a primary extractor 2. The extractor

advantageously comprises a vertical tower through which the feed hydrocarbon stream rises countercurrently to a downwardly moving body or stream of complex liquid.

The complex liquid is introduced to the upper portion of the extractor through a pipe 3 from a source which will be referred to later.

The complex is introduced to the extractor in the proportion of about 2 to 4 volumes of complex per volume of feed hydrocarbon mixture. The extraction in the extractor 2 is carried out at a temperature in the range of about 60-120° F. and at a pressure which may be in the range from atmospheric to 200 pounds per square inch gauge.

Provision may be made for continuously discharging used complex liquid from the system in an amount substantially equivalent to the amount of fresh complex being formed in situ.

As a result of the countercurrent contact occurring within the extractor 2, extract and raffinate phases are formed. The raffinate phase consists essentially of paraffin and naphthene hydrocarbons and is continuously discharged from the top of the extractor through a pipe 7.

The extract phase comprises complex and extract hydrocarbons, the extract hydrocarbons amounting to from about 80 to 90 volume per cent of aromatics, the remainder being non-aromatics. This extract phase is continuously drawn off from the bottom of the tower through a pipe 8 to a secondary extractor 10 wherein it is subjected to the first stage washing action.

A wash solvent consisting essentially of saturated hydrocarbons boiling below 175° F. is conducted from a source not shown through a pipe 12 to the lower portion of the extractor 10. The wash solvent is introduced in the proportion of about 1 volume of solvent to 10 or 15 volumes of primary extract phase. The wash solvent rises through the tower countercurrently to the descending primary extract phase at a temperature in the range about 60 to 120° F. and under a pressure ranging from atmospheric to 200 pounds gauge.

Under these conditions the saturated extract hydrocarbons which are coextensive in boiling range with the aromatic extract hydrocarbons are displaced from the primary extract phase in the form of a secondary raffinate. This secondary raffinate is continuously discharged through a pipe 13.

The secondary extract phase accumulating in the bottom of the extractor 10 comprises complex, primary extract hydrocarbons and some wash solvent. The wash solvent retained in the secondary extract phase will be approximately equal in volume to the saturated hydrocarbons displaced therefrom. It is continuously removed through a pipe 14 and conducted to the upper portion of a tertiary extractor 15 which is advantageously operated under conditions of temperature and pressure within the ranges described for the secondary extractor 10.

Another stream of wash solvent liquid is conducted from the pipe 12 through a branch pipe 16 to the lower portion of the extractor 15 and is introduced thereto in the proportion of about 1 to 3 volumes of solvent per volume of secondary extract phase.

The volume of secondary extract phase flowing through the pipe 14 is substantially equal to the volume of primary extract phase flowing through the pipe 8 and will range from 2½ to 5½ times the volume of feed hydrocarbon

mixture entering the extractor 2 through the pipe 1.

As a result of the washing treatment in the extractor 15, substantially all of the aromatic constituents extracted by the complex from the feed hydrocarbons in extractor 2 are displaced to form a tertiary raffinate which is continuously discharged through a pipe 18 from the top of the extractor 15.

10 The stripped complex containing some wash solvent liquid is continuously discharged from the bottom of the extractor 15 through a pipe 19 and is recycled all or in part through a branch pipe 20 which communicates with the previously mentioned pipe 3. That portion which is not recycled and which may be regarded as used complex may be discharged from the system at this point.

15 Referring again to the secondary extractor 10, the secondary raffinate is conducted through the pipe 13 and may be recycled all or in part through a branch pipe 25 and pipe 1 to the primary extractor 2. In this way the small amount of aromatic hydrocarbons that may be present in the secondary raffinate are extracted therefrom upon further contact with the complex liquid. The recycled non-aromatic hydrocarbons are ultimately discharged as raffinate through the pipe 7.

20 On the other hand, provision may be made for passing the secondary raffinate all or in part to a fractionator unit 26 indicated in broken lines for the purpose of separating the wash solvent from the aromatic hydrocarbons by fractional distillation. The aromatic hydrocarbons may be segregated as a plurality of separate fractions as indicated. In such case, provision may be made for recycling the separated aromatic fractions all or in part to the primary extractor 2.

25 The tertiary raffinate discharged from the extractor 15 through the pipe 18 is likewise passed to a fractionator 30 also shown in broken lines. The tertiary raffinate is also subjected to fractional distillation in order to recover hydrogen chloride, and also to remove wash solvent from the aromatic hydrocarbons. The latter may be obtained as any number of separate fractions.

30 The separated wash solvent is recycled through a pipe 31 to the pipe 12 for reuse in the primary and secondary washing stages.

35 Thus by way of example, the aromatic content of the extracted hydrocarbons leaving the primary extractor 2 will be about 82 to 87 volume per cent, while the aromatic content of the final extract hydrocarbons from the three stage system will be about 91 to 97%. On the other hand, by omitting the secondary extraction, the final extract from the fractionation unit will have the same composition as that of the extract hydrocarbons from the primary extraction.

40 While mention has been made of using a wash solvent which is lower boiling than the feed hydrocarbon mixture passing to the extractor 2, nevertheless it is contemplated that the wash solvent may be a hydrocarbon or hydrocarbon mixture boiling in the range above that of the feed hydrocarbons. The object is to use a wash solvent which is outside the boiling range of the hydrocarbons which are to be displaced from the complex and which subsequently can be separated readily from the displaced hydrocarbons by fractional distillation.

45 The feed hydrocarbon mixture may be any naphtha fraction containing benzene, toluene and higher molecular weight hydrocarbons, and it is contemplated that the process may be em-
70
75

ployed for extracting aromatic constituents from hydrocarbon mixtures boiling above the range of naphtha.

The process is advantageously employed in conjunction with the isomerization or reforming of aromatic hydrocarbons such as xylenes or xylene fractions of naphtha. The xylenes may be obtained in substantially concentrated form by the present process and then subjected to treatment with an aluminum halide catalyst under elevated temperature conditions so as to effect isomerization and other desired reforming reactions whereby the aromatic hydrocarbons are converted into hydrocarbons of increased value for blending with other gasoline hydrocarbons in the manufacture of high grade gasoline. The reforming catalyst may comprise aluminum halide-hydrocarbon complex promoted with a hydrogen halide and the reaction may be carried out with temperatures in the range 180 to 300° F. The used complex from the reforming action may be used as the solvent extracting medium in the primary extractor 2.

Instead of aluminum halide, other complex forming aluminum halides may be used such as aluminum bromide. Also other hydrogen halide promoters may be used besides hydrogen chloride.

Provision may be made for the addition, in small amounts, of some fresh complex through the pipe 32 in order to compensate for losses. Due to the relatively low temperatures complex formation in situ may not be equal to complex losses. The made-up aluminum halide is added in small amounts so as to maintain the heat of hydrolysis of the complex in the system up to the desired level.

Obviously many modifications and variations of the invention, as hereinbefore set forth, may be made without departing from the spirit and scope thereof, and therefore only such limitations should be imposed as are indicated in the appended claims.

I claim:

1. A process for extracting aromatic hydrocarbons from feed hydrocarbon mixtures of aromatic and non-aromatic hydrocarbons which comprises subjecting a naphtha feed hydrocarbon mixture boiling in the range above about 175° F. and containing about 10 to 80 volume per cent aromatics to contact at a temperature of about 60 to 120° F. with an aluminum halide-hydrocarbon complex of the Friedel-Crafts type having a heat of hydrolysis of about 290 to 330 calories per gram of complex, forming a primary extract phase comprising complex, aromatic and some non-aromatic hydrocarbons, and a primary raffinate phase consisting essentially of non-aromatic hydrocarbons, discharging the primary raffinate phase, subjecting the primary extract phase to countercurrent contact with substantially less than an equal volume of a wash solvent consisting essentially of saturated petroleum hydrocarbons at a temperature in the range about 60 to 120° F. such that non-aromatic extract hydrocarbons are displaced therefrom leaving a secondary extract phase comprising complex, aromatic primary extract hydrocarbons, and a small amount of wash solvent, discharging the displaced hydrocarbons, and subjecting the secondary extract phase to countercurrent washing with a further quantity of said wash solvent in the proportion from about 1 to 3 volumes of solvent per volume of secondary extract phase under substantially similar conditions such as to

displace said aromatic primary extract hydrocarbons from the complex.

2. The process according to claim 1 in which the complex is aluminum chloride-hydrocarbon complex.

3. A continuous process for extracting aromatic hydrocarbons from feed mixtures of aromatic and non-aromatic hydrocarbons which comprises passing a naphtha feed mixture boiling in the range above about 175° F. through a primary extraction zone in contact with an aluminum halide-hydrocarbon complex of the Friedel-Crafts type having a heat of hydrolysis of about 290 to 330 calories per gram of complex, removing from the primary extraction zone a stream of primary extract phase comprising complex, aromatic and some non-aromatic hydrocarbons, separately removing from the primary extraction zone primary raffinate phase consisting essentially of non-aromatic hydrocarbons, passing the removed primary extract phase through a secondary extraction zone in countercurrent contact with a wash solvent liquid consisting essentially of saturated petroleum hydrocarbons and in the proportion of about 1 volume of solvent per 10 to 15 volumes of primary extract phase, effecting said countercurrent contact at a temperature in the range about 60 to 120° F., removing from the secondary extraction zone a secondary extract phase comprising complex and aromatic primary extract hydrocarbons substantially free from non-aromatic primary extract hydrocarbons, removing from the secondary extraction zone a secondary raffinate consisting essentially of wash solvent and non-aromatic primary extract hydrocarbons, passing the removed secondary extract phase through a tertiary extraction zone in countercurrent contact with another stream of said wash solvent liquid in the proportion of about 1 to 3 volumes of wash solvent per volume of secondary extract phase, removing from the tertiary extraction zone a tertiary extract phase consisting essentially of stripped complex, removing from the tertiary extraction zone a raffinate phase consisting essentially of said wash solvent and aromatic primary extract hydrocarbons and recycling said stripped complex at least in part to the primary extraction zone.

4. A continuous process for extracting aromatic hydrocarbons from feed mixtures of aromatic and non-aromatic hydrocarbons which comprises passing a naphtha feed mixture boiling in the range above about 175° F. through a primary extraction zone in contact with an aluminum halide-hydrocarbon complex of the Friedel-Crafts type having a heat of hydrolysis of about 290 to 330 calories per gram of complex, removing from the primary extraction zone a stream of primary extract phase comprising complex, aromatic and some non-aromatic hydrocarbons, separately removing from the primary extraction zone primary raffinate phase consisting essentially of non-aromatic hydrocarbons, passing the removed primary extract phase through a secondary extraction zone in countercurrent contact with a wash solvent liquid consisting essentially of saturated petroleum hydrocarbons and in the proportion of about 1 volume of solvent per 10 to 15 volumes of primary extract phase, effecting said countercurrent contact at a temperature in the range about 60 to 120° F., removing from the secondary extraction zone a secondary extract phase comprising complex and aromatic primary extract hydrocarbons substantially free from non-aromatic primary extract

hydrocarbons, removing from the secondary extraction zone a secondary raffinate consisting essentially of said wash solvent and non-aromatic primary extract hydrocarbons, passing the removed secondary extract phase through a tertiary extraction zone in countercurrent contact with another stream of said wash solvent liquid under substantially similar temperature conditions and in the proportion of about 1 to 3 volumes of solvent per volume of secondary extract phase, removing from the tertiary extraction zone a tertiary extract phase consisting essentially of stripped complex, removing from the tertiary extraction zone a raffinate phase consisting essentially of said wash solvent and aromatic primary extract hydrocarbons, recycling said stripped complex at least in part to the primary extraction zone, fractionating from the secondary and tertiary raffinate phases said wash solvent liquid and recycling the recovered wash solvent liquid to the secondary and tertiary extraction zones.

5. A process for extracting aromatic hydrocarbons from feed hydrocarbon mixtures of aromatic and non-aromatic hydrocarbons which comprises subjecting a naphtha feed hydrocarbon mixture boiling in the range above about 175° F. and containing from about 10 to 80 volume per cent aromatics to contact at a temperature of about 20 60 to 120° F. with an aluminum halide-hydrocar-

10
